GOLFER'S EXERCISE DEVICE

Joseph W. Thiel, 2975 S. Hudson St.,
Denver, Colo. 80222

Filed Nov. 13, 1972, Ser. No. 306,164

Term of patent 14 years

Int. Cl. D21—02

U.S. Cl. D34—5 CB

FIG. 1 is a perspective looking down and to the left upon the golfer's exercise device;

FIG. 2 is a front elevation view;

FIG. 3 is a top view; and

FIG. 4 is a bottom plan view.

The right and left side elevations and the rear elevation are identical to the front elevation shown.

I claim:

The ornamental design for a golfer's exercise device, as shown and described.
